UNITED STATES PATENT OFFICE.

LUCIEN A. MARSH, OF MILL VALLEY, CALIFORNIA.

GAME BOARD.

Application filed November 21, 1922. Serial No. 602,346.

To all whom it may concern:

Be it known that I, LUCIEN A. MARSH, a citizen of the United States, residing at Mill Valley, county of Marin, and State of California, have invented new and useful Improvements in Game Boards, of which the following is a specification.

The present invention is particularly concerned with a game board designed to expedite the playing of the oriental game commonly known as Mah jongg or Chinese checkers. This game is played with a number of flat oblong playing pieces, which, at the beginning of the game are placed in four single rows arranged to form a perfect square. In the game this is termed building the wall. The sides of this square each comprises an equal number of the playing pieces and for the convenience of all of the players it is desirable that the square be formed as nearly as possible in the center of the table or game board so as to insure accuracy and uniformity in the setting up of the pieces and to provide each player with an equal and adequate amount of playing space between the square and the edge of the board or table.

It has been found difficult and tedious to arrange the playing pieces in proper position and correct number to form the square, usually requiring considerable time which detracts from the players' interest in the game. Therefore, it is the principal object of the present invention to provide a game board particularly adapted for the playing of the game Mah jongg, which board is provided with means so arranged that walls of the playing pieces may be easily and quickly arranged and trued in correct proportions and location.

The invention contemplates the use of game board having its playing surface formed with means arranged in square formation to accommodate a predetermined number of playing pieces.

One form which the invention may assume is exemplified in the following description and illustrated by way of example in the accompanying drawings, in which:

Fig. 1 is a view in plan of the preferred form of the invention, with parts broken away to more clearly disclose its construction.

Fig. 2 is a view in section taken on line 2—2 of Fig. 1.

Fig. 3 is a similar view taken on line 3—3 of Fig. 1.

Fig. 4 is a perspective view of the channel filler member.

Fig. 5 is a similar view of the operating slide.

Fig. 6 is a perspective view of one of the playing pieces.

Referring more particularly to the accompanying drawings, 10 designates a game board of preferred proportions, having a playing surface 11 and raised marginal edge 12. The board here shown is formed with connected channels 14 of equal dimensions arranged in a square as shown. Although other means might be used if desired the square formed by the channels is preferably located centrally of the board so as to provide playing spaces 15 of equal area on all four sides of the square.

The raised marginal edges of the board is formed by side members 16 secured about the perimeter of the board. The side members may be of any height sufficient to maintain the board slightly elevated from its support. In this instance the side members are rabbeted along their inner surface to accommodate the top of a standard card table, as shown in dotted lines at 17 in Figure 2. These tables are fitted with legs 18 and are of a proportion agreeing with the surface area of a board for playing Mah jongg.

The oriental game of Mah jongg alluded to, in some respects resembles the game known as dominoes, inasmuch as it is played with flat oblong playing pieces 18^a of equal size. One surface of these pieces is marked with distinctive characters or illustrations, representing different factors of the game. In commencing the game, the playing pieces are arranged in four connected straight rows forming a square to build what is termed a wall. It is necessary that the rows contain an equal number of pieces and it is for this reason that the playing surface of the board 10 is formed with the channels 14. The dimensions of the inner edge of each channel exactly agrees with the overall dimension of a row of pieces built of a predetermined number.

In the connected channels 14, is mounted a vertically movable filler member 19 which may be raised so that its upper surface is flush with the playing surface of the board or lowered below the board surface so as to

provide recesses for the reception of the playing pieces as described.

It should be stated that it is necessary at times for the surface of the board to be unbroken so that the playing pieces may be shuffled about with their characterized faces down, this takes place previous to starting a game, and if desired these fillers may be used to delineate the square without forming the channel.

Secured beneath the playing board are a plurality of brace members 20 which serve to firmly brace the board and to guide a reciprocable slide 21. This slide is formed of rigidly connected end members 22 and side members 23, the latter are guided in recesses 24 formed in the brace members 20. The slide is positioned directly below the filler 19 and is provided with cams 25 which co-operate with cams 26 on the filler to raise and lower the latter when the slide is reciprocated. The forward movement of the slide, which is intended to raise the filler, is limited by the engagement of the end member 22 and the brace 20^a as shown in Fig. 1. The forward movement is sufficient for the cams to raise the upper surface of the filler 19 flush with the playing surface of the board.

Reference being had to Fig. 3 it is seen that the inward movement of the slide is limited by the front end member 22 engaging the brace 20^b. When the slide is in its innermost position the upper surface of the filler is a distance below the surface of playing board forming the recesses described for the accommodation of the playing pieces.

The slide may be reciprocated by a rod 26^a fitted with a knob 27 located at one side of the game board.

In use, the device is mounted on a suitable support and playing pieces of the game are spread out over the playing surface of the board and shuffled. During this operation the filler is maintained flush with the surface of the board.

It is obvious that the raised marginal edge of the board will prevent the pieces from falling over the edge of the board and becoming lost.

When the pieces have been sufficiently shuffled, the filler 19 may be lowered forming connected channels to define a square into which channels the pieces are placed to build a wall. As the channel is of a width only slightly greater than the length of the pieces and of a length to accommodate a required number of the pieces, it is obvious that the wall may be easily and quickly built and will contain the correct number of pieces.

It should be stated that the game may be played with two different quantities of playing pieces, and to accommodate the smaller

quantity. The fillers are marked at the corners as at 28. The distance between these marks on each side of the square is sufficient to accommodate a certain known number of playing pieces.

From the foregoing it is obvious that I have provided a comparatively simple game board upon which walls of playing pieces may be easily and quickly arranged. Also, that the walls will contain a predetermined number of playing pieces without necessitating counting by the players.

While I have shown and described the preferred form of my invention as now known to me, it is to be understood that various changes in the construction, combination and arrangement of the various parts employed may be made by those skilled in the art, without departing from the spirit of the invention as defined by the appended claims.

Having thus described my invention, what I claim and desire to secure by Letters Patent is:

1. In a game board for use in playing a game employing flat oblong playing pieces, said board comprising a playing surface, guide means formed around the center of said playing surface and normally interrupting said playing surface whereby to assist in forming four walls of said playing pieces arranged at right angles, and means for operating said guide means to dispose the same in a position uninterrupted said playing surface.

2. A game board having a playing surface, said surface being formed with a plurality of elongated comparatively shallow recesses arranged to form a square, and a movable member forming the bottom of said recesses and means for operating said member whereby it may be raised flush with the playing surface of the board.

3. A game board having a playing surface, said surface being formed with a plurality of elongated connected recesses arranged in a square, a movable member mounted in said recesses forming the bottom thereof, and operable means for maintaining the member flush with the playing surface or maintaining it a certain distance below the playing surface.

4. A game board having a playing surface, said surface being formed with a plurality of elongated connected slots arranged in a square, a filler frame mounted in said slots, a reciprocable slide supporting said filler frame, and cooperating cam means interposed between the filler frame and the slide whereby movement of the slide in one direction will raise the filler frame flush with the playing surface and movement of the slide in the opposite direction will lower the frame to a distance below the play-

ing surface whereby to form a plurality of elongated connected recesses.

5. A device of the character described comprising a flat game board top constituting a playing field, side members secured around the perimeter of the top and projecting a distance below the same, a plurality of elongated rectangular slots formed in the game board top and arranged at 10 right angles to each other, a movable member in each slot, operable means for raising and lowering said members in the slots whereby they may be maintained flush with the playing surface of the game board top or a distance below the same to form guide 15 channels to receive playing pieces of the game, said side members being rabbeted along their inner surfaces at their lower edges to receive and embrace a table top 20 whereby to support the game board top at a distance above the table top.

6. A game board having a playing surface, said surface being formed with a plurality of elongated slots arranged at right angles to each other, a bottom member for each slot, and operable means for optionally controlling said bottom members whereby

they may be maintained flush with the playing surface or a distance below the same.

7. A game board for use in playing a game employing flat oblong playing pieces, 30 said board comprising a flat top constituting a playing surface, said top being cut to form a square at its center, the portion of the top immediately surrounding said square 35 being vertically movable, and means for vertically moving said movable portion of the top whereby the marginal edges of said square will constitute guides against which walls of said playing pieces may be built, 40 the length of the sides of said square being such as to accommodate a predetermined number of playing pieces.

8. A game board for use in playing a game employing flat oblong playing pieces, 45 said board comprising a flat top constituting a playing surface, and means for raising or lowering portions of said top to form guide means arranged in a square about the center of the top, said guide means being adapted 50 to assist in forming walls containing equal numbers of playing pieces.
